(57) **CLAIM**

(21) Appl. No.: **29/089,037**

The ornamental design for an enclosure for information
recorder and locator beacon, as shown and described.

(22) Filed: **Jun. 5, 1998**

DESCRIPTION

(51) **LOC (9) Cl.** 10-04

FIG. 1 is a perspective view of an enclosure for information
recorder and locator beacon showing our new design;
FIG. 2 is a top plan view thereof, the bottom plan view being
a mirror image;

(52) **U.S. Cl.** D10/67; D10/65; D10/70; D10/83;
D10/85; D10/96; D10/46; D10/49; D10/52;
D10/53; D10/98

FIG. 3 is a left side elevational view thereof, the right side
elevational view being a mirror image;

(58) **Field of Classification Search** D10/46,
D10/49, 52, 53, 65, 67, 70, 75, 83, 85, 96,
D10/98; 348/117, 144, E7.026, E7.031,
348/E7.86, E7.091; 386/E5.069; 375/240.12;
701/3, 10, 35

FIG. 4 is a rear elevational view;

See application file for complete search history.

FIG. 5 is a front elevational view thereof;

(56) **References Cited**

FIG. 6 is a perspective view of an alternative embodiment of
the invention; and,

U.S. PATENT DOCUMENTS

FIG. 7 is a right side elevational view thereof, the left side
elevational view being a mirror image.

2007/0100516 A1 * 5/2007 Olzak 701/14
2007/0124042 A1 * 5/2007 Monroe 701/35

Enclosure for Information Recorder and Locator Beacon can
be used to protect flight data and cockpit voice recordings
from physical damage due to a crash or other incident and to
send out a locator beacon signal to searchers.
